12,065

Dec. 21. 1880

DES 12065

UNITED STATES PATENT OFFICE.

HENRY J. DAVIES, OF BROOKLYN, NEW YORK.

DESIGN FOR A CLOCK-STAND.

SPECIFICATION forming part of Design No. 12,065, dated December 21, 1880.

Application filed October 21, 1880. Term of patent 7 years.

To all whom it may concern:

Be it known that I, HENRY J. DAVIES, of Brooklyn, in the county of Kings and State of New York, have originated and produced a new 5 and Improved Design for a Clock-Stand, of which the following is a specification.

As clearly shown in the accompanying drawing, which represents a clock-stand embodying my design, the principal elements thereof are 10 of a nautical character. The base of the stand is composed of an oblong angular portion, A, having at one end a representation of the prow of an ancient galley, a, supporting a compass, b, and supporting at the other end a capstan, 15 c. Upon the side of the base is a representation of a marine scene, comprising a light-house and vessels.

The clock case and dial B are supported upon a standard, C. (Represented as consisting of a 20 mirror surrounded by a rope or cable frame.) In front of the standard C, and below the dial, is a steering-wheel, D, mounted in a support, e, consisting of two dolphins and a trident, and upon each side of the wheel is a helmsman, 25 E, the man on the right side of said wheel having both hands extended toward the wheel and the man on the left side thereof having one hand extended toward the wheel. Below the clock-dial B are two flags, F F, and extending 30 above the dial, and apparently in the background, is a mast, G, a yard, H, and sail I.

What I claim as new, and desire to secure by Letters Patent, is—

1. A design for the base of a clock-stand,

consisting of the oblong angular portion A and 35 the prow a, as specified.

2. A design for the base of a clock-stand, consisting of the oblong angular portion A, having a marine scene upon its side, the prow a, the compass b, and the capstan c, as specified. 40

3. A design for a clock-stand, consisting of the dial B, the standard C, supporting the dial, the wheel D, arranged in front of the standard and entirely below the dial, and the helmsmen E, 45 arranged upon opposite sides of the wheel, and also entirely below the dial, as specified.

4. A design for a clock-stand, consisting of the mirror-standard C, having a cable-frame, d, the wheel D, arranged in front of the standard, and the dolphin and trident support e, all arranged below the dial, as specified. 50

5. A design for a clock-stand, consisting of the dial B, the standard C, the flags F F, the mast G, the yard H, and the sail I, as specified.

6. A design for a clock-stand, consisting of 55 the oblong base portion A, the prow a, the compass b, the capstan c, the dial B, the standard C, the wheel D, the dolphin and trident support e, the helmsmen E E, the flags F F, the mast G, the yard H, and the sail I, as specified. 60

7. The design for the ornamentation of a clock-stand, consisting of the mast G, the yard H, and the sail I, all arranged above the dial, as specified.

HENRY J. DAVIES.
